United States Patent

Des. 239,475

Patented Apr. 13, 1976

239,475

GIRDLE

Jack J. Lo Cascio, Bayonne, N.J., assignor to International Playtex, Inc., New York, N.Y.

Filed Oct. 3, 1974, Ser. No. 511,865

Term of patent 14 years

Int. Cl. D2—01

U.S. Cl. D2—2

FIG. 1

FIG. 2

FIG. 3

FIG. 1 is a front perspective view of a girdle showing my new design;

FIG. 2 is a rear perspective view; and

FIG. 3 is a right side elevational view, the left side being a mirror image thereof.

I claim:

The ornamental design for a girdle, substantially as shown and described.
